CLAIM

The ornamental design for a speaker housing, as shown and described.

DESCRIPTION

FIG. 1 is a front view of a speaker housing, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top, front perspective view thereof.

The broken lines in the figures illustrate the portions of the design that form no part of the claimed design.
